CLAIM

The ornamental design for a display panel of an electronic device with a changeable computer generated icon, as shown and described.

DESCRIPTION

The file of this patent contains at least one drawing or photograph executed in color. Copies of this patent with color drawings/photographs will be provided by the Office upon request and payment of the necessary fee.

FIG. 1 shows a first embodiment of a display panel of an electronic device with a changeable computer generated icon, showing our new design;

FIG. 2 shows a second embodiment of a display panel of an electronic device with a changeable computer generated icon; and,

FIG. 3 shows a third embodiment of a display panel of an electronic device with a changeable computer generated icon.

The design comprises a changeable computer generated icon on a display panel, such as a liquid crystal display panel, of an electronic device; the device arranged to provide information in real-time to a driver of a vehicle in relation to their driving style.

The broken lines shown in FIGS. 1-3 illustrate the display panel of an electronic device and form no part of the claimed design.
